UNITED STATES PATENT OFFICE.

WILLIAM CLOW, OF INDEPENDENCE, MISSOURI.

AUTOPLOW.

1,088,404.

Specification of Letters Patent. Patented Feb. 24, 1914.

Original application filed March 2, 1911, Serial No. 611,833. Divided and this application filed April 1, 1912. Serial No. 687,706.

To all whom it may concern:

Be it known that I, WILLIAM CLOW, a citizen of the United States, residing at Independence, in the county of Jackson and State of Missouri, have invented certain new and useful Improvements in Autoplows, of which the following is a specification.

My invention relates to auto plows, and the present invention is a division from a parent application filed Mar. 2, 1911, Serial No. 611,833.

One object of the invention is to provide a motor driven plow having two traction-wheels so located as to obtain the maximum weight thereon and travel upon the comparatively firm subsoil at the bottom of the furrows turned by the plow.

A further object is to provide novel mechanism for steering one of the traction-wheels and adjusting the same vertically to control the depth of the plow-shares in the soil.

Other objects of the invention will herein-after appear, and in order that said invention may be fully understood, reference will now be made to the accompanying drawings, in which:

Figure 1 is a side elevation of a gang plow constructed in accordance with my invention, the motor being removed. Fig. 2 is a plan view of my improved plow with a portion of the platform broken away and the motor removed. Fig. 3 is a rear elevation of the steering traction-wheel and a subsoiling appliance arranged in the rear of said traction wheel. Fig. 4 is a section on line IV—IV of Fig. 2, showing the steering traction-wheel, part of the drive gearing therefor, and the subsoiling device. Fig. 5 is an enlarged vertical section on line V—V of Fig. 2 of the steering traction-wheel and its axle mounting. Fig. 6 is a detail vertical elevation of the steering chain shaft and worm-wheel, the bearing of the shaft being in section. Fig. 7 is a detail section on line VII of Fig. 2.

1 designates the main frame of my auto plow, said frame being substantially rhomboidal in plan and preferably constructed of metallic beams to successfully withstand the various strains imposed thereon. Frame 1 is covered by a main platform 2, having an extension 3, upon which a seat 4 is mounted for the convenience of the operator. Frame 1 is supported by a rear traction-wheel 5, a small land-wheel 6 on the same side of the

frame as said traction-wheel 5, and a front steering traction-wheel 7 arranged diagonally across the frame from the traction-wheel 5, as shown on Fig. 2. The traction-wheels 5 and 7 are arranged to run in furrows, while the land-wheel 6 runs on unplowed land, the normal relative height of the wheels when plowing being shown on Fig. 1.

8 designates a plurality of plows, each having a separate mechanism for raising and lowering relatively to the frame, said mechanisms being operable simultaneously by a single lever 9, or individually by separate levers 9^a. As said mechanisms are fully set forth in the parent application, a detail description herein is deemed unnecessary.

The mechanisms just referred to are not designed for holding the plow-shares in intermediate working positions; but means have been provided for that purpose, which shift the main frame 1 up and down at the forward end thereof. Referring more particularly to Figs. 2 and 5, it will be seen that a yoke 10 is secured vertically to the forward right side of the main frame 1. Connecting the ends of said yoke is a shaft 11 upon which is swiveled and slidably-mounted an axle-block 12 carrying an axle 12^a, upon which the front traction-wheel 7 is mounted. Integral with the inner end of axle-block 12 is a forwardly-extending bracket 13. A hand-lever 14 is operably-secured to the upper end of the yoke 10 by a pivot 15, and fulcrumed at 16 upon a link 17 pivotally secured at its lower end to a lug 18 projecting rearwardly from the axle block 12. Lever 14 is locked in any of its adjusted positions by a notched sector 19, secured to platform 2. Sufficient looseness exists at the pivotal points 16 and 18, to allow wheel 7 to turn to the right or left without turning lever 14 therewith. As the yoke 10 is secured to the main frame 1, it is apparent that when the lever 14 is operated, it will raise or lower said yoke and said frame, the shaft 11 sliding through the axle-block 12.

The foregoing mechanism is shown to act on the right side of the main frame 1 only.

The left side of the main frame 1 is vertically-adjusted by mechanism embodying an upwardly bent axle 20 of the land-wheel 6, which axle extends slidably through a

block 21, fixed to the adjacent side of the main frame 1. Fixed upon the top of axle 20 is a block 22, to which a hand-lever 23 is operably secured by a pivot 24, and said hand-lever is pivotally secured at its forward end to a downwardly-extending link 25, pivotally connected to the adjacent side of the main frame 1.

From the foregoing construction it is obvious that the land-wheel 6 may be adjusted vertically by means of the hand-lever 23, hence when said land-wheel 6 is raised upon the land, the pivot 24 becomes the fulcrum of the hand-lever, so that the frame 1 may be raised or lowered and thus regulate the depth of the plow-shares. After frame 1 has been adjusted the hand-lever 23 is locked from accidental movement by a sector 26. By means of the hand-levers 14 and 23, the traction-wheel 7 and the land-wheel 6 may be adjusted to raise or lower the gang of plows independent of the movements imparted by the mechanisms controlled by levers 9 and 9^a.

Referring now in detail to the propelling mechanism, 27 designates a main shaft driven by a suitable engine, not shown, and provided with two sprocket-wheels 28 and 29.

Fixedly mounted on the rear traction wheel 5 is a ring-gear 30 driven by a pinion 31 fixedly mounted upon a stub-shaft 32 journaled in a bearing 33, fixed upon the adjacent portion of the main frame 1. Fixed upon shaft 33 32 is a sprocket-wheel 34 driven by the sprocket-wheel 28 through the intermediacy of an endless sprocket-chain 35.

The forward traction-wheel 7, like the rear traction-wheel 5, is provided with a fixedly-mounted ring-gear 36 driven by a pinion 37. In line with the sprocket-wheel 29 is a sprocket-wheel 38 driven by sprocket-wheel 29 through the intermediacy of an endless sprocket-chain 39. Sprocket-wheel 38 is fixed upon a short shaft 40 journaled in bearings 41 and connected by a universal joint 42 to a tubular shaft 43. Slidably in shaft 43 is a square or splined shaft 44, connected by a universal joint 45 with a short shaft 46 journaled in the forward end of bracket 13 and upon which the pinion 37 is fixedly-mounted. The foregoing arrangement permits traction-wheel 7 to be driven from the sprocket-wheel 38 and at the same time move up or down so that it may travel on the land or in a furrow, and also describe a curve in steering the plow, independently of said sprocket-wheel 38.

As shown on Fig. 2, a steering-bar 47 is connected to the axle bracket 13 and extends transversely across the forward portion of the plow where it is pivotally-connected to an arm 48 swiveled in a block 40^a, secured to the axle 20. The steering-bar 47 is actuated by a chain 49, the intermediate portion of which is wound about a vertical steering-

shaft 50, journaled in a bearing 51 and provided at its upper end with a fixedly-mounted worm-wheel 52. Worm-wheel 52 intermeshes with a worm 53 fixed to the forward end of a rod 54, journaled in bearings 55 and provided at its rear end with a steering-wheel 56 within convenient reach of the operator.

Pivotally-connected to the axle block 12 and the axle 12^a is a U-shaped frame 57, which depends rearwardly and carries at its lower part a subsoiling appliance 58, to loosen the subsoil traversed by the front traction-wheel 7. The subsoiling appliance 58 is held in or out of the ground by a curved brace 59, pivotally-secured at its lower end to frame 57 and having key-hole slots 60 arranged at different heights therein, adapted to receive the headed end of a stud 61 projecting from an adjacent portion of extension 3.

Operation: To start plowing on unfurrowed land, the operator raises the front wheel 6 and the front traction-wheel 7 until the shares are at the required depth. The traction-wheel 5 follows in the first furrow, and when there is a furrow for the front traction-wheel 7, the same is lowered to the level of the plow-shares. Thus it will be understood that both traction-wheels travel on the comparatively firm bottom of the furrows, so that there will be little or-no tendency for said traction-wheels to slip. The raising and lowering of the front wheel 6 and the traction-wheel 7 is accomplished through the intermediacy of the levers 23 and 14, respectively, and said wheels are turned simultaneously to guide the plow either to the right or to the left by turning the hand-wheel 56 in the proper direction.

Having thus described my invention what I claim and desire to secure by Letters Patent, is:

1. In an auto plow, a frame, a traction wheel at each end thereof and arranged to travel in a furrow, means for adjusting the front traction wheel vertically, a motor geared to the rear traction wheel, a toothed gear fixed to the front traction wheel, a pinion intermeshing with said tooth gear to drive the same, said pinion being vertically adjustable with the front traction wheel, and self adjusting shafting driven by the motor and upon which said pinion is mounted.

2. In an auto plow, a frame, a traction wheel at each end thereof and arranged to travel in a furrow, means for adjusting the front traction wheel vertically, said front traction wheel also being capable of being turned to the right or the left to guide the plow, a motor geared to the rear traction wheel, a tooth gear fixed to the front traction wheel, a pinion intermeshing with said tooth gear to drive the same, said pinion being mounted for vertical adjustment with

said front traction wheel and capable of turning to the right or left therewith, self-adjusting shafting upon which said pinion is mounted, and a sprocket wheel geared to the motor and mounted upon said shafting to drive the same.

3. In an auto plow, a frame, a traction wheel at each end thereof and arranged to travel in a furrow, means for adjusting the 10 front traction wheel vertically, a motor geared to the rear traction wheel, a tooth gear fixed to the front traction wheel, a pinion intermeshing with said tooth gear to drive the same, said pinion being vertically 15 adjustable with the front traction wheel, a

short shaft upon which said pinion is mounted, a bearing for said shaft, a telescopic shaft loosely connected to said short shaft, a sprocket wheel geared to the motor, a short journaled shaft upon which said 20 sprocket wheel is mounted, and a yielding connection between said short shaft and the telescopic shaft.

In testimony whereof I affix my signature, in the presence of two witnesses.

WILLIAM CLOW.
